COMBINED WALL PLAQUE AND CHRISTMAS CARD HOLDER

Leon Cohen, Brooklyn, N. Y.

Application September 2, 1954, Serial No. 32,136

Term of patent 14 years

(Cl. D29—1)

FIG.2

Fig. 1 is a front elevational view of a combined wall plaque and Christmas card holder showing my new design, and

Fig. 2 is a side elevational view thereof.

I claim:

The ornamental design for a combined wall plaque and Christmas card holder, substantially as shown.
